UNITED STATES PATENT OFFICE.

JOHN J. HIGGINS, OF NEW YORK, N. Y., ASSIGNOR TO E. & H. T. ANTHONY & COMPANY, OF SAME PLACE.

PHOTOGRAPHIC CAMERA.

SPECIFICATION forming part of Letters Patent No. 371,458, dated October 11, 1887.

Application filed July 13, 1887. Serial No. 214,137. (No model.)

To all whom it may concern:

Be it known that I, JOHN J. HIGGINS, a citizen of the United States, and a resident of New York city, in the county of New York and State of New York, have invented certain new and useful Improvements in Photographic Cameras, of which the following is a specification.

My invention relates to improvements in the construction of photographic cameras, and especially those termed "detective" or "portable," and also to certain new and useful devices connected therewith.

My invention consists in making the body of the camera in two or more parts united by hinges or equivalent devices, whereby the camera-box may be opened and the interior thereof utilized as a receptacle, in which the plate-holders and other accessories may be conveniently carried; also, by the separation of the body of the camera into distinct and, so to speak, independent parts, the substitution of a lens of one focus for a lens of a different focus is effected by simply changing the front of the camera, as hereinafter stated, and I thus avoid the necessity of purchasing and transporting two complete cameras.

In the drawings, Figure 1 illustrates a bottom plan view of the camera, it also showing a frame having a "view-lens" detached from the rest of the camera at the right-hand side of the figure. Fig. 2 illustrates a side plan view of the same parts. Fig. 3 illustrates a horizontal section, taken through the rear part of the camera, showing the push-button for outwardly starting the plate holders. Fig. 4 illustrates a front view of the frame holding a shorter focus-lens. Fig. 5 illustrates a front view of the camera, the lid containing the light-excluder having been opened. Fig. 6 illustrates a view, looking into the camera-box when opened, showing the arrangement of the plate-holders therein. Fig. 7 illustrates a side sectional view of the rear part of the camera, illustrating the method employed for holding the lid in the rear end of the camera open. Fig. 8 illustrates a side view of the supplemental case for holding the plate-holders. Fig. 9 illustrates an end view of the supplemental case for containing the plate-holders. Fig. 10 illustrates a view of the interior of the front of the

camera, showing the setting mechanism for the shutter, the shutter being set ready for operation. Fig. 11 illustrates a like view of the interior of the front of the camera, the shutter having been tripped. Fig. 12 illustrates details of construction of the shutter-setting mechanism.

In the drawings the same reference letters refer to the same parts in all the figures.

I will first describe my camera as provided with a comparatively long focus-lens.

A is the camera-box proper. It is made in two parts, B B, hinged together at C C.

D D is the handle, made in two parts, one being attached to one part of the box and the other to the other part thereof.

D' is a catch to hold the parts of the box together when closed. It may be of any desired construction.

E is the front part of the camera, adapted to be opened to give access to the lens, shutter, and mechanism therewith connected.

F is the usual side door, through which the plate holders are introduced into the rear of the camera for exposure.

G, Fig. 3, is a little button placed at the opposite side of the camera from the door F. It is provided with a short shank, which passes through a hole made in the side of the camera, and is enlarged on its inner end, as at H, so that it cannot drop out.

I is a plate-holder in position ready to take a picture.

J is the focusing mechanism for adjustment of the lens. It forms no part of this invention, and need not be specifically explained.

K, Figs. 4 and 5, is the usual "finder."

L is the light-excluding shield located in front of the lens. It is a thin plate of metal, wood, or other suitable material, and is pivoted at M.

N is a slide, which plays through a slot, N', Fig. 2, made in the side of the front of the camera E. The slide is provided with a push-button, O, on the outside of the camera. Its inner end is bifurcated, as shown, which bifurcation engages with a pin, O', on the shield L.

P is a little catch, which is screwed to the inside of the drop E, the free end whereof projects outwardly away from the frame, and is adapted to receive the edge of the shield L be-

neath it, so that when closed the shield will be sustained against pressure from without by this catch.

Q Q Q Q, Fig. 6, are guiding and shield supporting ribs attached to the inner walls of the rear half of the camera. They are so located that they will sustain one or more plate-holders (seen at R R) on each side between them and the sides of the camera, but outside of the field of the lens. Thus these plate-holders need not be removed from the camera during the taking of impressions.

S is a frame, preferably of card board, leather, or equivalent light and thin material, adapted to fit into the vacant space within the camera.

It is intended to contain the plate-holders which have to be removed during the taking of impressions. It is seen detached and filled with plate-holders R' R', &c., in Figs. 8 and 9.

There is a hole, T, made in its side, (see Fig. 8,) by means of which the plate-holders can be easily ejected therefrom by the finger.

U, Fig. 6, is the lens.

V, Fig. 7, is a small pivoted supporter for the lid at the rear end of the camera. By its use the lid may be sustained higher or lower, as required, to properly screen or protect the eyes of the operator, the better to see the rear of the plate. This is very useful in taking pictures out of doors.

The operation of the apparatus as thus far described is as follows: When starting to take impressions, the operator, instead of carrying the camera and also a separate package of plate-holders, as formerly, opens the camera-box and places the requisite number of plate-holders within it. Some of them may be placed behind the guiding and supporting ribs Q and others in the frame S, which is dropped into the vacant space between the outside plate-holders, R. The whole apparatus is easily carried by the handle D D. When desiring to take impressions, the camera is again opened, the case S containing the plate-holders is removed, the camera-box is then again closed, a plate-holder is then inserted in the rear of the camera, and the impression is taken in the usual way. During these operations the light-excluding shield L is very conveniently operated from the exterior of the camera by means of the push-button O, as shown in dotted lines, Fig. 5, and when it is desired to remove the plate-holders and plate from the rear of the camera pressure upon the push-button G will push the plate-holder forward over the little ledge W on the opposite side of the camera, which engages with a rabbet on the plate-holder, thus avoiding the awkward feature in the use of these apparatuses of having to press the plate-holder rearwardly against the springs X, and at the same time draw it outwardly through the door F with the same hand.

The foregoing has, as stated, pertained to the use of the comparatively long focus lens in connection with the other parts of the apparatus. Referring now to the use of a lens having a shorter focus, as shown at a, Figs. 1,

2, and 4, its construction is well known and does not require special explanation. The finder K, the light excluder L, and the other parts shown in Fig. 4 are all well understood, and these parts and the other requisite parts may be made as desired. In order to adapt it to use in my peculiar combination, however, I provide this part of the camera with separable hinges (seen at b b) or other interchangeable interlocking connecting devices, and with half a handle (seen at e,) and I make the hinges C C, which connect the two parts of the camera-box A, separable and in such manner that the uniting-pin d, which connects the two leaves of the hinges, may be readily withdrawn, so that the part B, which contains the longer focus-lens, can be readily separated from the rear part of the camera by simply withdrawing the pin from the hinges and the frame containing the shorter focus-lens be readily substituted. A convenient method of doing this is to extend the uniting-pin of the hinge in the form of an eye or ring, as shown in Fig. 1, by which it can be readily withdrawn and the two leaves of the hinge disengaged one from the other.

Figs. 10, 11, and 12 illustrate the mechanism for resetting and tripping the shutter when taking instantaneous pictures.

a is the shutter. It is pivoted at b, and provided with an aperture, e, and with notches d d' on its periphery.

e is the lens.

f is a catch pivoted at g, and normally pressed upward by a spring, h.

i is a sleeve which fits snugly over the lens-holding tube, but may be turned thereon. To it is fastened a plate spring, j, the free end of which projects in a substantially radial manner from the edge of the sleeve i. The shutter a has a pin, a', on its front surface, which, when the shutter is rotated on its axis b', comes in contact with the spring j, and bends it downwardly and around the sleeve i, thus putting it under tension. The spring catch f, engaging with the notches d d' on the periphery of the shutter, holds it in such position as may be desired until released. Then the spring j instantly throws the shutter back again to its normal position, causing the aperture e therein to pass quickly across the hole in rear of the lens, thus producing the instantaneous exposure desired.

For a more full description of the parts I refer to the United States Letters Patent granted to me, assignor to E. & H. T. Anthony & Co., dated June 7, 1887, No. 364,413.

In order that the shutter a may be set and tripped from the exterior of the camera, I provide the following mechanism:

k is a curved lever, preferably cut from sheet brass.

l is a downwardly-extending finger extending from the lever k.

m is a spring, which is attached at one end to the lower end of the finger l and at its other end to the frame of the camera. The lever k is extended through a hole in the side

of the frame, and is provided with a pull button, *n*, on its end.

o is a spring attached to the frame, which bears on a small pin, *p*, fastened to the lever *k*. This spring normally presses the lever *k* downwardly, maintaining it in contact with an extension of the pin *a'*, which projects from the rear side of the shutter.

q is an upwardly-extending stud on the upper side of the lever *k*, which, when the lever is drawn out nearly to the limit of its movement, engages with a deflector, *r*, attached to the frame, whereby the spring *o* is aided in pressing the shutter farther around until the notch *d'* engages with the catch *f*. This is desirable when the tension on the spring *j* is at its greatest, as explained in my said former patent.

s is a curved lever, also preferably cut from sheet-brass. It is pivoted at *t* to the frame, and curving around the lens-case, as shown, engages, by means of a pin projecting from it, with the end of the spring-catch *f*. A spring, *u*, normally throws this lever *t* upwardly, so that its weight does not rest on the catch, which might tend to release it from the notches in the shutter inopportunely.

v is a rod, which projects through a passage-way or hole made in the side of the frame and slides therein. Its inner end rests against the upper end of the bent lever *s*.

w, Fig. 12, is a stop-pin, which projects from the rear side of the shutter and strikes against a like pin in a plate, *x*, thus stopping the shutter from going too far around under the action of the spring *j*. Any other suitable stop or friction device may be used for this purpose.

The operation of these devices is as follows: Upon pulling the button *n* outwardly the lever *k*, acting on the rearward extension of the pin *a'* in the shutter, and aided by the spring *o* and the deflector *r*, causes the shutter to rotate on its axis until the spring-catch *f* enters the first notch, *d*. During this movement the pin *a'* in the shutter, having come in contact with the spring *j*, has pressed it partially around the periphery of the cap *i* and has put it under slight tension. At this stage in the rotation of the shutter the aperture *c*

therein will be coincident with the hole in the shield in rear of the lens and the apparatus will be in proper condition for taking long-exposure pictures. To adapt the apparatus to take instantaneous pictures, (which is the special intent of this part of my invention,) the bar *k* is pulled still farther out into the position shown in dotted lines in Fig. 10. The spring-catch *f* readily moves out of the notch *d*, allowing for this further revolution of the shutter, owing to the rear edge of the notch *d* being beveled off, as shown in Fig. 11. It then rests in the second notch, *d'*, and the spring *j* is put under increased tension, and the aperture *c* in the shutter is carried over to the left beyond the center of the lens, and the solid part of the shutter covers the opening in the rear of the lens, excluding the light. To make

the instantaneous exposure, pressure is applied to the end of the rod *v*, which, acting on the curved lever *s*, disengages the catch *f* from the notch *d'*, and the spring *j* then instantly throws the shutter back again to its original position, the picture being taken during the transit of the aperture *c* across the center of the lens.

It is of course not essential that the guiding and supporting ribs *Q* should be employed. The case *S* may be used alone, or the case *S* may be dispensed with and the space which it occupies may be filled with loose holders or other accessories.

Having described my invention, I claim—

1. A portable photographic-camera box having a vacant unoccupied space internally adapted to receive plate-holders used with the camera, the said box being divided between the lens and the exposure-plate, whereby it may be opened and the said space utilized for the reception of plate-holders or other accessories, substantially as set forth.

2. A photographic camera made in two or more parts divided between the lens and the exposed plate, whereby the box may be opened for the reception of plate-holders, and provided with ribs, grooves, frames, or equivalent devices for the holding and retention of the plate-holders, said plate-holders being outside the field of view, substantially as and for the purposes set forth.

3. A photographic camera the box whereof is made in two or more parts, the division or divisions occurring between the lens and the exposure plate, whereby the interior space of the camera box may be utilized for the reception of plate-holders or other accessories, and a detachably-attached lens-holding part or frame, whereby a lens of one character may be replaced by a lens of a different character, substantially as set forth.

4. The described improvement in camera-boxes, consisting in two or more lens-holding parts or frames, each provided with detachable connecting devices which engage with counterpart connecting devices on the body of the camera, whereby lenses of different foci may be used in connection with the same camera-box, substantially as set forth.

5. The combination, in a camera, of a pivoted light-excluder, *L*, and a sliding button, *O*, outside of the camera which engages with the light-excluder eccentric to the pivot by means of a spindle passing through the side of the camera-box, substantially as and for the purposes set forth.

6. The combination, in a camera, of a push-button projecting beyond the side of the camera opposite the door through which the plate-holders are introduced in the rear of the camera, the inner end of the push-button engaging with the edge of the plate-holder when in position within the camera, whereby the plate-holder may be started outwardly from the camera by applying pressure to the push-button, substantially as set forth.

7. The combination, in a camera, of a piv-

oted shutter provided with a light-admitting aperture, a sliding lever or rod operated from the exterior of the frame and engaged with the shutter for its rotation, a spring put under tension by the rotation of the shutter, a spring-catch which engages with notches on the shutter and holds it against the stress of the spring, and means for releasing the catch, substantially as set forth.

10. S. The combination, in a camera, of a pivoted shutter provided with a light-admitting aperture, a sliding lever or rod operated from the exterior of the frame and engaged with the shutter for its rotation, a spring put un-

der tension by the rotation of the shutter, a 15 spring-catch which engages with notches on the shutter and holds it against the stress of the spring, and a rod or lever operated from the exterior of the frame for the release of the catch, substantially as set forth. 20

Signed at New York, in the county of New York and State of New York, this 8th day of July, A. D. 1887.

JOHN J. HIGGINS.
